(57) CLAIM

The ornamental design for a package having a double band quadruple loop gift wrapping article, as shown and described.

DESCRIPTION

FIG. 1 is a perspective view of a package having a double band quadruple loop gift wrapping article.

FIG. 2 is a top view of the package having a double band quadruple loop gift wrapping article of FIG. 1, shown separately for completeness of illustration.

FIG. 3 is a side view thereof.

FIG. 4 is a perspective end view thereof.

FIG. 5 is a cross-sectional view thereof, taken along and in the direction of the section cut line as shown in FIG. 3; and, FIG. 6 is a perspective view of the package having a double band quadruple loop gift wrapping article of FIG. 2.

1 Claim, 3 Drawing Sheets
